UNITED STATES PATENT OFFICE.

FREDERICK BRANDT, OF MOUNT VERNON, NEW YORK.

COMPOSITION WALL COVERING.

Application filed May 11, 1927. Serial No. 190,515.

This invention relates to improvements in wall coverings formed of suitable plastic material, such as cement and adapted to be applied to the walls of buildings and for use 5 either as inside or outside coverings.

The invention has for its salient object to provide a simple, inexpensive and practical wall covering in the form of slabs or boards which can be easily and securely fixed to 10 the frame or other structure on which they are to be mounted.

Another object of the invention is to provide a board or slab of composition material so constructed that the edges thereof will 15 be securely interlocked with adjacent boards or slabs, thereby preventing separation thereof and also warping or separation from the structure on which the boards or slabs are mounted.

20 Another object of the invention is to provide a cover of the character described so constructed and arranged that the joints between adjacent units will be securely held together and the material of each unit will 25 not crack or open up.

Further objects of the invention will appear from the following specification taken 30 in connection with the drawings, which form a part of this application, and in which

35 Fig. 1 is a sectional elevation showing a plurality of boards or slabs constructed in accordance with the invention mounted on a frame structure;

Fig. 2 is a sectional elevation taken at 40 right angles to Fig. 1;

Fig. 3 is a perspective view partly broken away showing adjacent edges of a pair of slabs; and

45 Fig. 4 is a front elevation partly broken away and partly in section showing the construction of one of the units.

The invention briefly described consists of 50 forming wall covering units, such as slabs or boards of suitable plastic composition or cement reinforced throughout the length and width thereof with metallic reinforcing material, such as wire screen or expanded metal.

55 The edges of the slabs or boards are formed in such a manner that they will interlock and will overlap so that the securing means will pass through the interlocked edges and also through the reinforcing material in both of the slabs. Further details of the invention will appear from the following description.

Each of the units 10 is formed of suitable

material of a plastic nature such as cement, sand, ground cork, ground cinders, asbestos or like material and of such a nature that the slab or unit will be to a certain extent 60 flexible.

Each unit, furthermore, has embedded therein and extending throughout the length and width thereof, a sheet 11 of reinforcing material, such as wire screen or expanded 65 metal. The edges of each unit are so formed that the unit will interlock with the adjacent unit and in Fig. 1, the edge 12 of the unit 10 is undercut as shown at 13, tapered or inclined as shown at 14 and again cut 70 away at an angle as shown at 15. Thus a projecting tapered portion 18 is formed at each edge of the slab or board, the tapered projecting portion 18 at one edge being disposed adjacent one surface of the slab of 75 the portion 18 and the other edge being disposed adjacent the other surface of the slab. It will be noted from the showing in Figs. 1 and 2 that the reinforcing material 11 extends diagonally in the slab from the extreme edge of one projecting portion 18 to the extreme edge of the other projecting portion 18.

In fitting the slabs and securing them to a beam or supporting structure 20, the edge 80 of one unit is fitted into the edge of the adjacent unit so that the projecting portions 18 of the two units overlap and the securing means, such as nails or screws 21 are then passed through the overlapping portions and 85 also pass through the reinforcing members in the adjacent units and overlapping edges. In this way it is practically impossible for the adjacent units to pull apart and the nails or screws firmly and fixedly secure 90 the slabs or units to the supporting structure.

The adjacent units may, if desired, be secured together in slightly spaced relation to leave a narrow space 23 therebetween. This space is filled with grout or other suitable plastic material of such a nature that any expansion or contraction of the adjacent units will be taken care of thereby.

The outer surfaces of the units may be finished in any desired manner and may, if 100 desired, be provided with recesses 25 causing the slabs to have the appearance of brick work.

It will be evident from the showing in Figs. 1 and 2 that the disposition of the projecting portion 18 of one slab within the undercut portion 13 of the adjacent slab

and, furthermore, the juxtaposition of the remaining portions of the adjacent edges of the two slabs will effectively interlock the edges and counteract any tendency of the 5 slabs to pull away from each other or the supporting structure. Furthermore, the filling of plastic or flexible composition in the space between the adjacent edges will take care of any expansion or contraction of the 10 units and will not interfere in any way with the nailing or securing of the units to the supporting structure.

Although one specific embodiment of the invention has been particularly shown and 15 described, it will be understood that the invention is capable of modification and that changes in the construction and in the arrangement of the various cooperating parts may be made without departing from the 20 spirit or scope of the invention, as expressed in the following claims.

What I claim is:

1. The combination with a wall supporting structure of a covering therefor, consisting of a plurality of slabs, each slab having its edge portions overlapping the edge portions of adjacent slabs and having a metallic reinforcing member therein extending to the edge of the overlapping portions, and securing means extending through the overlapping edges and through the reinforcing members in the overlapping edge portions and into said supporting structure.

2. The combination with a wall supporting structure of a covering therefor, consisting of a plurality of slabs, each slab having its edge portions tapered and overlapping the edge portions of adjacent slabs and having a metallic reinforcing member

therein extending to the edge of the overlapping portions, and securing means for each of the overlapping edges extending through said edges and through the reinforcing members in each of the overlapping edge portions and into said supporting structure.

3. The combination with a wall supporting structure of a covering therefor consisting of slabs formed of cement-like material, each having tapered, undercut edge portions and each having embedded therein a metallic reinforcing member extending diagonally throughout the length and width thereof and to the extreme edges thereof into the undercut portions.

4. The combination with a wall supporting structure of a covering therefor, consisting of a plurality of slabs, each slab being formed of cement-like material and having its edge portions overlapping the edge portions of adjacent slabs and having a metallic reinforcing member therein extending to the edge of the overlapping portions, and securing means extending through the overlapping edges and through the reinforcing members in the overlapping edge portions and into said supporting structure.

5. The combination with a wall supporting structure of a covering therefor, comprising a plurality of slabs having substantially duplicate undercut, interlocking edge portions, the portions of one slab being in overlapping juxtaposed relation with the similar edge portions of an adjacent slab, whereby to prevent lateral movement of one slab with respect to its adjacent slab, and common securing means for both slabs extending through said portions.

FREDERICK BRANDT.
